FIG. 3

FIG. 4

FIG. 5

FIG. 6

FIGURE 1 is a front view of a typewriter or the like illustrating my new design;

FIGURE 2 is a top plan view thereof;

FIGURE 3 is a left side view thereof;

FIGURE 4 is a right side view thereof with the cover shown in the open position;

FIGURE 5 is a rear perspective view thereof; and

FIGURE 6 is a front view similar to the view of FIGURE 1 showing the typewriter or the like with the cover open.

The dot-dash lines on the drawing indicate that the rows of keys extend across the keyboard.

I claim:

The ornamental design for a typewriter or the like, substantially as shown and described.
